Inventor:

August Goertz,

By Drake & Co Cliffo's.

UNITED STATES PATENT OFFICE.

AUGUST GOERTZ, OF NEWARK, NEW JERSEY.

DESIGN FOR A PURSE-FRAME.

SPECIFICATION forming part of Design No. 21,164, dated November 10, 1891.

Application filed January 29, 1891. Serial No. 379,597. Term of patent 7 years.

To all whom it may concern:

Be it known that I, AUGUST GOERTZ, a citizen of the United States, residing at Newark, in the county of Essex and State of New Jersey, have invented and produced a new and original Design for Metal Frames for Purses; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

In the accompanying drawings, which are deemed sufficient to illustrate the invention, Figure 1 is a plan of the newly-designed frame; and Fig. 2 is a plan of the same, showing the frame open.

The leading feature of the design consists

in a purse-frame having an interior and exterior outline of approximately heart shape, as shown.

In said drawings, b indicates the frame, which is interiorly and exteriorly heart-shaped in outline, b^2 being the heart-shaped interior opening, b^3 b^4 the scallops at one side of the frame, and b^4 the rounded point at the opposite side of said frame. The cover a is correspondingly heart-shaped in plan.

What I claim as new is—

The design for a purse-frame, as herein described and shown.

In testimony that I claim the foregoing I have hereunto set my hand this 22d day of January, 1891.

AUGUST GOERTZ.
